UNITED STATES PATENT OFFICE.

CARL HAGGENMILLER, OF MUNICH, GERMANY.

TABULATING MECHANISM.

Application filed March 14, 1916. Serial No. 84,046.

To all whom it may concern:

Be it known that I, CARL HAGGENMILLER, citizen of Germany, residing at Munich, Bavaria, Germany, have invented certain new and useful Improvements in Tabulating Mechanism (for which I have filed application in Germany, Feb. 29th, 1912; Austria, Dec. 9th, 1915; Hungary, Dec. 16th, 1915; Switzerland, Dec. 2nd, 1915; Holland, Dec. 10, 1915; Sweden, Dec. 23rd, 1915; France, Jan. 6th, 1916; Great Britain, Dec. 15th, 1915); and I do hereby declare the following to be a full, clear, and exact description of the invention, such as will enable others skilled in the art to which it appertains to make and use the same.

Devices are known for classifying or dis-integrating statistics in connection with which a perforated band is employed, the 20 perforations of which represent the statistical results or figures, the said band being guided over a rotating roller cooperating with suitable circuit closing devices for counting or adding up the figures given.

25 The object of the present invention is to provide a device for registering statistics of various kinds, and includes a perforated band adapted to be passed over or in relation to contact making devices, whereby 30 when contact is made, suitable registering devices are actuated in correspondence with the number of contacts made. The device is constructed to be capable of registering what I term either "single countings" or 35 "combination countings;" the former being the registration of but a single kind of statistics, as for example the number of male inhabitants of a district, while the latter is the registration of various kinds of statistics, as for example, the number of male 40 inhabitants, their occupation, their creed and race.

Thus, for instance, if a census of the population is to be taken, it is possible with 45 great rapidity, and at one and the same time, to determine the number of all male and female, single and married or widowed inhabitants, or to determine at the same time, together with or separately from the 50 general census, a certain combination of conditions or qualities of the inhabitants, for instance, the men who may be Protestants, unmarried, or are Bavarians or the like or

are 21 years of age, or belong to the standing army.

55 The time necessary for each registration is the same in every case whether two or fifty different qualities are to be registered. This is attained by first registering consecutively the qualities of each person in connection with a census or the characteristic features of the objects in connection with other statistical material, by means of perforations in the endless band made consecutively in horizontal spaces of the band produced by longitudinal and transverse lines marked on the said band and then passing the band thus marked through an electric contact system.

55 By this means, the employment of individual perforated cards—as such are necessary with other systems, particularly in connection with the Hollerith system—is obviated, as is also the employment of the sorting and subdivided boxes which are necessary in connection with the system. In addition to an exact sifting of the material to indicate population, a geographic sorting is rendered possible, for instance, the registration of the personal properties or 70 qualities of a locality, community or municipal district, of a town or the like; or a chronological arrangement is possible which permits of the chronological registration of objects between two periods of time (for instance, in connection with popular statistics, the number of persons who died of a certain disease in a month). It is also possible to register certain groups of persons or objects in closed consecutive groups, as for instance, 75 in connection with households, where it is necessary to determine the number of single households, family households, or those of public buildings or in taking a census to determine the number and class of dwellings. 80 85 90 95

100 In the accompanying drawings a device is illustrated for carrying out the present process, Fig. 1 being a side elevation partly in section and Fig. 2 a plan of the device, Fig. 3 is a diagram of the electric connections of the device of Figs. 1 and 2. Figs. 4, 5 and 6 show other electrical diagrams and Fig. 7 shows in part side elevation an arrangement adapted for the system illustrated in Fig. 6.

105 The band 2 provided with the perfora-

tions 1 representing the properties of the various persons or objects is wound on a reel 4 provided with a crank handle 3, and is guided from the reel 4 over a guide roller 5 to the roller 6 for the single counting, said latter roller being made of metal constituting a good electric conductor. It passes then over a second tension roller 7 to the roller 8 for the combination counting and then over 10 further guide rollers 9 and 10 to the take-up reel 11 which is also provided with a hand crank 12.

Above the roller 6 for the single counting is arranged a suitable number of double arm 15 levers 13—in the present case twelve—which are insulated from each other by means of vulcanite sleeves 14 or the like and are rotatably mounted on the spindles 15. The inner arms of the levers 13 are bifurcated and 20 their upper parts 17 are held against a shaft 18 of insulating material by means of springs 16 attached to the outer arms, their lower arms 19 being provided with contact rollers 20. If, as shown in Fig. 1 the parts 25 17 of the levers 13 rest on the flattened part of the spindle 18, the rollers 20 will be in contact with the contact rollers 6. If the shaft 18 is turned 180° by means of the handle 21 (Fig. 2), the levers 13 will be raised, 30 and the rollers 20 will be moved out of contact with roller 6.

The roller 8 for the combination counting consists of a suitable number of discs 22—in the present case twelve—made of good conducting material and separated from each other by insulating discs 23. Each disc 22 cooperates with a flat spring 24, the latter being mounted on a cross bar 25 of vulcanite or other non-conducting material.

40 Above the contact roller 8 are arranged a corresponding number of levers 26—in the present case twelve. The levers 26 are insulated on the shaft 27 and have downwardly extending arms 28 carrying rollers 29 while the ends of the levers are connected to flat springs 31, attached to a bridge piece 32 and insulated from each other.

50 Contact pins 33 cooperate with the twelve flat springs 31, said pins being mounted on a bridge of insulating material, and also co-operable with the springs 31 are hand levers 34 made of insulating material and pivotally supported on the plates 35. A stop bar 36 is provided for the hand levers 34. Rods 35 are linked to the flat springs 31, which rods have insulated ends resting on flat springs 36 (Fig. 3) adapted to contact with flat springs 37. The springs 36 and 37 are mounted respectively on bars 38 and 39 of 60 conducting material.

The contact lever system for single counting is arranged next to the contact lever mechanism for the combination counting.

This single counting lever system consists of twelve handles 41 pivotally support-

ed on the plates 40, the said handles being of insulating material and their lower ends resting on flat springs 42, attached to and insulated from each other on the bridge 43. The ends of the flat springs 42 extend above 70 the ends of flat springs 45 attached to a bar 44 which is also of insulating material. A shaft 47 of insulating material and rotatable to the extent of 180° by means of a lever 46 permits all of the flat springs 42 to be 75 simultaneously depressed on to the flat springs 45 to make contact.

Corresponding with the twelve contact levers 41 and 34 for single and combination counting, are twelve counting or registering 80 mechanisms, one only of which is shown in Figs. 1 and 2, at the right hand side. Each of these counting mechanisms consists of a counter magnet 48, the armature 49 of which forms a pawl, adapted by means of suitable 85 gearing 50 to advance the counting wheels 51 one tooth further at each contact closure. Any suitable counting mechanism may be employed and the extent of movement of the same may be selected at will and the results may be read off through the recesses 52 of the walls 53.

Inside the housing, on the upper part of which the contact springs 42 and 45 and their parts are mounted, a switch device is provided, which, as will be seen from Fig. 3, consists of a sliding fork 54 with handle 55 and indicator 56, to the shanks of which are connected contact levers 58. These contact levers, which are pivoted at 57 and are insulated from the fork 54, correspond in number to the contact handles 41 or the pairs of springs 42, 45. The levers 58 may be connected with the contacts 59 for single counting or with the contacts 60 for combination counting arranged next to them and connected up in series, according to the position of the fork 54 which may be adjusted to bring the pointer 56 to the line for single counting as in the present case or to the line for combination counting. 61 indicates a further contact lever for the switch fork, which serves as current maker and breaker for the contacts 62 and 63 for single and combination counting. 64 indicates the 100 source of current, which may be a battery. The device may however be connected up to any illuminating circuit.

The operation of the device will now be described with reference to the diagram 120 illustrated in Fig. 3.

Assuming, for instance, that a single counting is to be effected and that the levers 19, 13 are in contact with the rollers 6 (as is illustrated in Figs. 1-3,) so that the rollers 20 extend through the holes 1 of the paper band 2 passing over the roller 6, then, if for instance, the counting is to be effected by the levers 41 having marked thereon the figures "1," "4," "8," "11" and their corre- 125 130

sponding counter mechanisms 48, 49, 50, 51, these four levers must first be shifted to the right, by which means the corresponding flat springs 42 will be placed in contact with 5 the corresponding flat springs 45.

When the rollers 20 which correspond with the contact levers 41 having the numbers "1," "4," "8" and "11" marked thereon pass through the corresponding holes 1 of the 10 registering band 2 and make contact with the roller 6, the following circuits will be formed to wit: The + pole of the battery 64, conductor 65, roller 6, and roller 20, the levers 19, 13 corresponding with the contact 15 levers 41 marked with "1," "4," "8" and "11," conductors 66, contacts 59, contact levers 58, conductors 67, contact springs 42, 45, conductors 68, windings 48, conductor 69, switch contact 62 for single counting, 20 switch lever 61, conductor 70, — pole of the battery 64.

The armatures 49 of the four magnets 48 receiving current, and corresponding with the contact levers 41 having the numbers 25 "1," "4," "8" and "11" marked thereon will be attracted and thus the corresponding counting mechanisms 50 and 51 will be operated as often as the four corresponding rollers 20 cooperating with the band 2, make 30 contact with the roller 6 through the perforations 1 of the registering band.

If a combination counting is to be effected, the levers 13, 19 and the roller 20 are first raised off the contact roller 6, which 35 is done by turning the lever 21, 180°, so that the round part of the insulating shaft 18 will raise the levers 13, 19, and the rollers 20 off the roller 6.

Assuming that, instead of the four contact levers 41 "1," "4," "8," "11," for the single counting, similarly numbered levers for a combination counting are to be used, then the contact levers 34 numbered "1," "4," "8," "11," for the combination counting 45 are shifted to the right thereby depressing the levers 26, 28, by means of the corresponding contact springs 31, which are moved out of contact with the corresponding contact pins 33, and as a result of depressing the levers 26, 28 the corresponding rollers 29 will be lowered to engage the contact discs 22 of the contact roller 8, and contact between the rollers 29 and the discs 22 will be made when the registering holes 1 of the band 2 55 permit. By depressing the flat springs 31, contact is made between the flat springs 36 and 37 and thus also between their conductive carrier bridges 38 and 39, by means of the rods 35. If the switch fork 54 is pushed 60 in so that the indicator 56 points to the line on the scale designated C for combination counting, the contact levers 58 will be shifted to the combination counter contacts 60, and the switch lever 61 will be placed on the 65 contact 63. If, for instance, the combination

is to be registered by the registering mechanism No. 6, then the contact lever 41 bearing No. 6 must be thrown over, so that the corresponding springs 42, 45 will come into contact with each other. 70

It will be noted from Fig. 3 that each conductor 75 leading to a contact pin 33 has a branch connected thereto leading to the next succeeding contact spring 31; and it will also be borne in mind that by rocking levers 34 numbered "1," "4," "8" and "11" about their pivots the contact between the pins 33 and the springs 31 at the positions of these levers will be broken. The circuit is then traceable thus:—From the 80 plus pole of the battery 64, conductor 71, series conductor 72, contacts 60, contact levers 58, conductor 67, springs 42 and 45 of lever number 6 of group 41, conductor 68, magnet winding 48 of indicator for said 85 contact lever number 6, conductor 69, connecting point 73 and conductor 74; the first spring 31, contact lever 28, first disc 22, spring 24, first conductor 75, then through the branch from first conductor 75 to the 90 second flat spring 31; through contact pin 33 to the second conductor 75, through the branch from second conductor 75 to the third flat spring 31, the third contact pin 33 to third conductor 75, the branch therefrom to the fourth spring 31 and as the contact between the latter and its corresponding pin 33 is broken the current will flow through 95 through the fourth lever 28, the disc 22, the spring 24, the fourth conductor 75, the 100 branch therefrom to the fifth spring 31, its contact pin 33, through its branch to the fifth conductor 75, through the branch from the fifth conductor 75 to the sixth spring 31, its contact pin 33, back through the 105 branch which connects the latter with the sixth conductor 75, from the latter to the seventh spring 31, its contact pin 33, back through the branch connecting the latter with the seventh conductor 75; from the 110 latter to the eighth spring 31 and as the contact between the latter and its corresponding contact pin 33 is broken, the current will flow to the eighth contact lever 28, eighth disc 22, eighth spring 24, eighth conductor 75, through the branch from the latter to the ninth spring 31, its contact pin 33, the branch connecting the latter with ninth conductor 75, from the latter to the tenth spring 31, its contact pin 33, back 115 through its branch to the tenth conductor 75; from the latter to the eleventh spring 31, and as the contact between it and its pin 33 is broken, the current will flow to the eleventh lever 28, eleventh disc 22, 120 eleventh spring 24, eleventh conductor 75, through the branch connecting the latter with the twelfth spring 31, the twelfth contact pin 33, the twelfth conductor 75; then through the connection 76 and conductor 77, 125 130

rail 39, springs 37 and 36, rail 38, conductor 78, contact 63, switch lever 61, conductor 70 and — pole of the battery 64.

The number of the combination may then be read off from the counter mechanism No. 6, which receives current at each combination.

In a similar manner any other desired combinations may be registered on each of the registering mechanisms by depressing the corresponding contact lever 41, in which connection since the flat springs 31 are always connected up in series by the conductors 75, the circuit through the combination roller 8 will always be similar to that described.

I have herein used the terms "single counting" and "combination counting" to distinguish between the registration of but a single kind of information, and the registration of a variety of data. An example of single counting would be the registration of the number of inhabitants of a given territory, without taking into account for example the sex, the religion, the occupation, or the citizenship of the people. In combination counting, however, all these qualities or characteristics of the inhabitants would be registered simultaneously. Assuming

that it be desired to determine the population of a certain territory, as well as the sex, the religion, the occupation and the citizenship of each inhabitant, then levers 1, 4, 8 and 11 of series 34 would be used; lever 1 being used to register sex, lever 4 religion, lever 8 occupation, and lever 11 citizenship. The tape 2 being apertured to correspond with the desired data, when a roller 29 makes contact with a disc 22

through such aperture, the mechanism of the appropriate register 49-53 shown at the right of Fig. 7 is actuated, and the particular information is thus registered. If it be assumed that lever number 6 of group 41 has been shifted to the right as shown in Fig. 1, registering mechanism number 6 will register the several data which it is desired to obtain by the combination counting. The operation of single counting has been above explained and need not be here repeated.

Of the systems illustrated in Figs. 4, 5, 6, that shown in Fig. 4 is for single counting, Fig. 5 for combination counting and Fig. 6 for single and combination counting.

In the diagram of Fig. 4, the contact roller for single counting does not, as was the case with Fig. 3, consist of a single metallic cylinder, but of a suitable number of metal discs 79 insulated one from another which influence the counting mechanism magnets 80 corresponding to magnets 48 of Figs. 1 and 3 by means of conductors 81 and 82 closed at times by contact levers 83 (corresponding to levers 41 in Figs. 1-3) and are connected up in series to a main cur-

rent conductor. 84 are the disc contacts corresponding to rollers 20 of Figs. 1 and 3 and 85 the drag springs of the discs 79, said springs corresponding to springs 24 of Figs. 1 and 3.

In the diagram for combination counting illustrated in Fig. 5, the magnets 80 of the counting mechanism are connected up in series by means of conductors 86 and 87 in a main current circuit. In this case the contact levers are indicated at 88 (corresponding to 34 in Figs. 1-3) the discs at 89, the disc contacts at 90 and the disc drag springs at 91. Thus every combination would be registered at all the counting mechanisms, immediately the corresponding combination contact levers 88 were thrown over or shifted. In order, however, to operate these counting mechanisms only, which correspond to the rows of holes selected by throwing over the corresponding contact levers for the desired combination counting, each contact lever 88 must be constructed as illustrated at 34 in Fig. 7.

To each handle lever 34 is linked by means of a collar 123, a downwardly extending rod 124, extending through the cover of the hollow bearing bracket and connected to one arm of a bell-crank lever 126 mounted at 125, to the other arm of which a rod 127 is linked. This rod connects with one arm of another bell-crank lever 128, the other arm of which carries a rod 129 which extends upwardly through the bearing socket and the counting mechanism stands and ends beneath the armature 49 of the counting mechanism magnet 80, i. e., it rests against the latter. By this means, when the circuit is made, all the counting mechanism magnets 80 will be excited, but only such of them will be able to attract the armature 49, as have been released by the shifting of the handle 34, in which case each of the connections 124, 126, 127, 128 and 129 will occupy the position shown in dotted lines.

Thus the counting of the combination will take place simultaneously at as many counting mechanisms as levers 34 have been operated, i. e., a number corresponding to the number of elements of the combination to be registered.

This is, however, of no importance and does not render the counting more difficult since all the counting mechanisms can be simultaneously returned to the zero position after having effected the registration.

In the arrangement illustrated in Fig. 6 one row only of counting magnets 80 is provided which is employed for single and combination counting and which are connected up to the operating current conductors in parallel in the first case and in series in the second case to the operating source of electricity.

With this object in view a contact lever

device is provided, consisting of two slide rods 95 and 96, suitably mounted on the base plate for the rest of the switch mechanism and connected to a double arm lever 94 5 mounted at 93 and provided with a handle 92 for adjusting the device.

Adjacent the rod 95 are mounted at 97, 97' insulated contact levers 98 and 99, which co-operate with contacts 100 and 101. To the 10 rod 96 are connected at 110 and 103 pivotally mounted and insulated levers 104 and 105, the number of which corresponds to the number of counter mechanisms. In single counting the upper arms of the levers 15 105 are in contact with the contacts 106^a, in combination counting, the lower arms of the bell-crank levers 105 lie on the contacts 106 for combination counting while the levers 104 make contact at 104^a. The position 20 of the contact levers 98, 99, 104, 105 illustrated in Fig. 6 is for combination counting.

Conductors 107 lead from the contacts 101 to the windings of the magnets 80, and conductors 108 connect up the contacts 100 to the contacts 84 of the discs 79 for single counting, whilst the disc drag springs 85 are connected up to the contacts 106^a of levers 105 by means of conductors 109 and conductors 111 lead from the pivots 103 of levers 105 to the magnets 80 of the counting mechanisms. Thus in single counting the latter lie next each other in the following like circuits: — pole of the source of electricity or juncture of the main conductor 97, 98, 100, 108, 84, 79, 85, 109, 106^a, 105, 103, 111, 80, 107, 101, 99, 97', + pole of the source of electricity or juncture of the main current conductor.

40 Thus as soon as a circuit is closed at 79, 84, the counting magnet 80 in the same will be excited and counting will take place on the counting mechanism selected, in a manner similar to that described in connection 45 with Fig. 3.

From the contacts 106 of the levers 105 for combination counting, conductors 112 lead to the contacts 90 of the discs 89 for combination counting, the springs 91 of which 50 are connected by conductors 113 to contacts 104^a of contact levers 104, from which conductors 111^a lead to the windings of the counting magnets 80, the other ends of said windings being connected by means of conductors 111 to the pivots 103 of contact levers 105, which are in contact with the contacts 106 in combination counting.

115 and 114 indicate two switch levers, the first of which is an ordinary hand switch 60 while the latter is attached near and insulated from the rod 95 and is turned simultaneously with the other contact levers 98, 99, 104, 105, connected to rods 95 and 96 when adjusted for combination or single 65 counting. The lever 114 serves for single

and combination counting and is connected up to the + pole of the source of electricity or main current conductor, so that it may always be brought into contact with contact 116, which is connected by the conductor 107 with the last counting mechanism magnet 80. The lever 115 serves for single counting only and cooperates with the contact 100 which is connected by a conductor 108 to the contact 84 of the first contact disc 75 79 for single counting. On the other hand, the spring 91 of the second to the last contact disc 89 for combination counting is connected by conductor 113 with the previous contact 104^a of the contact lever 104 and the drag spring 91 of the first contact disc 89 by the conductor 120 to the — pole of the source of electricity or the main current conductor.

Thus all the counting mechanism magnets 80 are in series with their respective combination contact discs 89 in the following circuit:—

— pole of the source of electricity or main current conductors 120, 91, 89, 90, 112, 106, 105, 103, 111, 80, 111^a, 110, 104, 104^a, 113, 91, 89, 90, 112, 106, 105, 103, 111, 80, 111^a, 110, 104, 104^a, 113 . . . (any desired number of the periods 91, 89, 90, 112, 106, 105, 103, 111, 80, 111^a, 110, 104, 104^a, 113) . . . 95 91, 89, 90, 112, 106, 105, 103, 111, 80, 107, 116, 114, + pole of the source of electricity or of the main current conductor. Since this course of the current is repeated at each combination counting, and exactly as with the diagram of Fig. 5 all the counting magnets 80 are excited, but cut out as far as the counting is concerned, it will be possible, by shifting the selecting lever, as in the case of the device illustrated in Fig. 7, to employ the corresponding counting mechanism 105 at will for registering the combination counting.

It will be understood that Figs. 4, 5 and 6 merely show a circuit arrangement which may be used in lieu of that of Fig. 3 for single and combination counting.

Of the rods 129 each lies with its upper end in a position to normally lock the armature 49 of the corresponding registering magnet 80, so that this armature cannot be 115 attracted by the registering magnet unless the operating lever (34) positively connected with such rod has been previously operated. By operating one of the levers 34 the corresponding armature 49 is freed. 120

As above stated Fig. 6 is merely another circuit arrangement which may be employed in lieu of that of Fig. 3. In this form a change of circuit from single counting (parallel circuit arrangement) to combination counting (series circuit arrangement) is effected by operating contact levers by means of the switching device 92, 93, 94, 95, 96.

It is to be noted that in the arrangement 130

of Fig. 6 selecting levers 34 having armature locking means as in Fig. 7 are employed, but in Fig. 6 these levers are omitted owing to the small size of this figure and also 5 because their arrangement is shown in Fig. 5 wherein selecting levers are denoted 88.

From the foregoing it will be noted this 10 alternative arrangement is merely a combination of the circuit arrangement of Fig. 4 for single counting with the circuit arrangement of Fig. 5 for combination counting, or in other words the circuit arrangements for single and combination counting which are shown combined in Fig. 6 appear 15 separated in Figs. 4 and 5.

I claim as my invention:—

1. In a tabulating mechanism for the purpose specified, the combination of a single-unit counting-station including a conducting 20 surface adapted to have a perforated band pass thereover, a combination counting-station including a conducting surface adapted to have said band pass thereover, registering mechanism, electrical connections from both of said stations to said 25 registering mechanism, and means for selectively connecting either of said stations electrically with said registering mechanism.

2. In a tabulating mechanism for the purpose specified, the combination of a single-unit counting-station including a conducting surface and contact members operatively related thereto, a combination counting-station including a conducting surface and contact members operatively related thereto, means for feeding a perforated band through 35 both of said stations between said conducting surfaces and the corresponding contacts, registering mechanism, electrical connections from both of said stations to said 40 registering mechanism, and means for selectively connecting desired contacts at either of said stations with said registering mechanism.

45 3. In a tabulating mechanism for the purpose specified, the combination of a single-unit counting-station including a conducting surface and contact members operatively related thereto, a combination counting-station including a conducting surface and contact members operatively related thereto, means for feeding a perforated band through 50 both of said stations between said conducting surfaces and the corresponding contacts, registering mechanism, means electrically connecting the contacts of the first mentioned station in parallel with said registering mechanism, and means electrically connecting the contacts of the second mentioned station in series with said registering mechanism.

60 4. In a tabulating mechanism for the purpose specified, the combination of a single-unit counting-station including a conduct-

ing surface and contact members operatively related thereto, a combination counting-station including a conducting surface and contact members operatively related thereto, means for feeding a perforated band through both of said stations between said 65 conducting surface and the corresponding contacts, registering mechanism, means electrically connecting the contacts of the first mentioned station in parallel with said registering mechanism, means electrically connecting the contacts of the second mentioned station in series with said registering mechanism, and switching mechanism adapted, when actuated, to selectively place the series of contacts at either of said stations into 70 circuit with said registering mechanism, whereby one registering mechanism is adapted to register the effective work of either of said stations.

5. In a tabulating mechanism for the purpose specified, the combination of a single-unit counting-station including a conducting surface and contact members operatively related thereto, a combination counting-station including a conducting surface and contact members operatively related thereto, means for feeding a perforated band through 75 both of said stations between said conducting surfaces and the corresponding contacts, registering mechanism, means electrically connecting the contacts of the first mentioned station in parallel with said registering mechanism, means electrically connecting the contacts of the second mentioned station in series with said registering mechanism, 80 switching mechanism adapted, when actuated, to selectively place the series of contacts at either of said stations into circuit with said registering mechanism, whereby one registering mechanism is adapted to 85 register the effective work of either of said stations, and means for selectively causing any of the contacts in circuit with said registering mechanism to actuate the latter.

6. In a tabulating mechanism for the purpose specified, the combination of a single-unit counting-station including a cylinder of conducting material and spring pressed contact members yielding urged towards 90 said cylinder, a combination counting station including a conducting surface and contacts operatively related thereto, means for passing a perforated band through both said stations over the conducting surfaces thereat, means whereby the contacts at the first mentioned station may be moved out of operative range of the said cylinder, registering mechanism, and means electrically connecting the contacts at both of said stations with 95 said registering mechanism.

7. In a tabulating mechanism for the purpose specified, the combination of a single-unit counting-station including a conducting

- surface and contacts operatively related thereto, a combination counting-station including a roller consisting of alternately arranged conducting and insulated discs, pivotedally supported levers having depending arms, contact rollers carried by said arms and adapted to contact with said conducting discs, means for passing a perforated band through both of said stations, registering mechanism, and means electrically connecting the contacts at said stations with said registering mechanism.
8. In a tabulating mechanism for the purpose specified, the combination of a single-unit counting-station including a cylinder of conducting material, contact members supported over said cylinder, means whereby said contact members may be moved out of operative range of said cylinder, a combination counting-station including a roller consisting of alternately arranged conducting and insulated discs, contact members pivoted over said conducting discs, means for passing a perforated band through said stations, registering mechanism, and means electrically connecting the contacts at said stations with said registering mechanism.
9. In a tabulating mechanism for the purpose specified, the combination of a single-unit counting station including a conducting surface and contact members operatively related thereto, a combination counting-station including a conducting surface and contact members operatively related thereto, means for feeding a perforated band through both of said stations between said conducting surfaces and the corresponding contacts, registering mechanism, means connecting the contacts of the first mentioned station in parallel to said registering mechanism, means connecting the contacts of the second mentioned station in series to said registering mechanism, means at the said second station for placing any of the contacts thereof into circuit with said registering mechanism, and means extraneous to said first station for placing any of the contacts of the latter into circuit with said registering mechanism.
10. In a tabulating mechanism, a record divided into a plurality of positions, one for each characteristic of which a registration is to be made covering a plurality of cases, indicia in said positions defining the characteristics of individual cases, a register common to said positions, an electrical circuit controlling device, a plurality of contacts in said device, one for each position of the record and operable by the indicia occurring therein, a circuit for operating said register, a plurality of branches through which said circuit may be completed, each of said branches including a different one of said contacts, and means for completing said circuit through any desired plurality of branches.
11. In a tabulating mechanism, a record divided into a plurality of positions, one for each characteristic of which a registration is to be made covering a plurality of cases, indicia in said positions defining the characteristics of individual cases, a register common to said positions, an electrical circuit controlling device, a plurality of contacts in said device, one for each position of the record and operable by the indicia occurring therein, a circuit for operating said register, a plurality of branches through which said circuit may be completed, each of said branches including a different one of said contacts, and means for completing said circuit through any desired plurality of branches.
12. In a tabulating mechanism, a record divided into a plurality of positions, one for each characteristic of which a registration is to be made covering a plurality of cases, indicia in said positions defining the characteristics of individual cases, a register common to said positions, an electrical circuit controlling device, a plurality of contacts in said device, one for each position of the record and operable by the indicia occurring therein, a circuit for operating said register, a plurality of branches through which said circuit may be completed, each of said branches including a different one of said contacts, a plurality of switches one for each branch, and means controlled by said switches for completing said circuit through any desired plurality of said branches.
13. In a tabulating mechanism, a record divided into a plurality of positions, one for each characteristic of which a registration is to be made covering a plurality of cases, indicia in said positions defining the characteristics of individual cases, an electrical circuit controlling device responsive to every one of said indicia, a plurality of registers, one for each position on said record, means controlled by said device for variably operating said registers in accordance with the indicia in the corresponding positions, and means for variably operating one of said registers in accordance with a certain predetermined combination of indicia in a plurality of positions on said record.
- In testimony whereof I hereunto affix my signature in the presence of two witnesses.
- CARL HAGGENMILLER.
- Witnesses:
- ARTHUR GUBE,
AUGUSTE DIEHL.
